SAMPLE DISPLAY BOARD FOR A LUGGAGE
HANDLE AND THE LIKE

Lou F. Marks, Pittsburgh, Pa., assignor to Bruce Molded
Plastic Products, Inc., Moon Run, Pa., a corporation of Pennsylvania

Filed June 1, 1965, Ser. No. 85,532

Term of patent 14 years

(Cl. D80—5)

Fig. 2.

Fig. 4.

Fig. 3.

FIG. 1 is a front elevation of the display board in accordance with the invention;

FIG. 2 is a top view of FIG. 1;

FIG. 3 is a right end view of FIG. 1; and

FIG. 4 is a vertical sectional view along line 4—4 of FIG. 1.

The broken line representation of a luggage handle in FIGS. 1, 2 and 3 is for the purpose of illustration only.

I claim:

The ornamental design for a sample display board for a luggage handle and the like, as shown and described.
